UNITED STATES PATENT OFFICE

JOHN H. McCANN, OF CHICAGO, ILLINOIS

PROTECTIVE COVER FOR PLUMBING FIXTURES

Application filed March 8, 1930. Serial No. 434,187.

This invention relates to covers for porcelain, marble, or vitreous coated plumbing fixtures, and more particularly to coverings that are adapted to be temporarily applied to the fixtures for protecting the same while the building in which they are to be employed is under construction. Many of these fixtures are installed prior to the completion of the plastering or tile-setting in the room, and some times even before the partitions are fixed in position. Under such conditions the fixtures are likely to become damaged by the workmen; accordingly, it is desirable that some form of covering be provided to prevent such injury.

The primary object of this invention is to provide an improved form of protective covering with means to prevent its unauthorized removal from the fixture thus insuring the latter against willful abuse, neglect or carelessness during construction work. Another object is to produce an improved protective covering of the character mentioned, designed and arranged for protecting both the inner surfaces and the laterally exposed external surfaces of the fixture. A further object is to produce an improved covering that is simple in construction, light, strong and durable, and capable of being used over and over again. It consists in certain features and elements of construction as herein shown and described, and as indicated by the claims.

In the drawings:

Figure 1 is a front elevation of a water tank provided with a protective cover embodying the present invention.

Figure 2 is a vertical section taken substantially as indicated at line 2-2 on Figure 1, showing the adjacent wall in section.

Figure 3 is a front elevation of a kitchen sink provided with my improved protective cover.

Figure 4 is a bottom plan view of the same.

Figure 5 is a vertical section through the kitchen sink and protective cover, taken substantially as indicated at line 5-5 on Figure 3, showing the adjacent vertical wall in section.

The protective covering, 35, illustrated in connection with the water tank fixture, 36,

shown in Figures 1 and 2, is a box-like structure having a front panel, 37, and connected vertical side walls, 38, and a horizontally extending top portion, 39. The members, 38 and 39, are dimensioned to accommodate the width of the tank and to substantially abut at their rear edges against the vertical wall, as indicated at A. Secured to the under side of the top flange, 39, is a suitable form of stop, herein shown as an angle clip, 40, located so as to engage the inner wall of the tank and thus prevent lateral removal of the protective covering. Secured to the lower edge of the front panel, 37, preferably to one side of the center, is a flexible tie member, 41, in the nature of a chain adapted to be trained around the outlet pipe, indicated at 42, and having one end connected to a shackle, 43, on the front panel by means of a padlock, 44, and adjacent the permanent connection of the other end of the chain to panel, 37, thus precluding unauthorized removal of the covering.

Figures 3, 4 and 5 illustrate a further form of my protective covering, 45, as applied to a kitchen sink, indicated at 46. For this construction the covering includes an inclined top portion, 47, terminating at its upper edge in a horizontally extending portion, 48, adapted to engage the top of the fixture and abutting against the vertical wall, indicated at B. The top portion has at its lower edge a rigid downwardly depending front flange, 49, overlapping the front of the sink and rigid end flanges, 50, connected thereto; said flanges 49 and 50 being dimensioned to extend slightly below the lower edge of the fixture.

By reason of the end flanges, 50, abutting against the vertical wall, the horizontal top portion, 48, assists in supporting the box-like covering in position on the fixture; and to prevent forward movement of the cover of the fixture, I provide a pair of downwardly depending clips, 51, on the under side of the inclined top portion, 47, positioned for engaging the inner vertical surface of the cavity of the sink fixture, as may be seen in Figure 5. The covering is locked to the fixture to preclude unauthorized removal by means consisting of a pair of rigid bars, 52, each formed

with an eye at one end engaged with an eye, 53, on the outside of the end flange, 50, adjacent its lower edge. Thence the bar extends horizontally in oblique direction under the lower edges of the front and end walls of the fixture. The opposite end of each of the bars, 52, is flattened to form an eye portion which is insertable through an eye or staple, 54, secured on the front flange, 49, of the cover; a locking bar, 55, is formed with a hooked end, 56, which engages one of the staples, 54, under the eye of the bar, 52, while the opposite end of the bar, 55, has a flattened eye portion which may be lapped under the flattened eye of the other bar, 52, on the other staple, 54, and retained by suitable padlock, 55^a. The bars, 52, are also provided with upwardly extending lugs or fingers, 52^a, positioned for engaging the inner surface of the front wall 25 of the fixture to supplement the stops, 51, in preventing its removal forwardly.

It will be understood that in all of the protective coverings for the various fixtures illustrated in Figures 1 to 5, the interior surfaces of the coverings are lined with suitable material such as felt so as to protect the finished surface of the fixtures against injury by abrasion such as might occur by placing on or removing the covering from the fixture, or due to the limited amount of movement even when it is locked in place thereon.

I claim:—

1. In combination with a plumbing fixture including a body having an upwardly open cavity and laterally exposed surfaces extending in different directions from each other; a protective cover including a main portion dimensioned to serve as a closure for the cavity, and depending flanges adapted to enclose the lateral surfaces, a rigid tie member connected to the flanges and arranged for engaging the lower edges of the fixture, and locking means arranged to preclude unauthorized removal of the cover.

2. In combination with a plumbing fixture including a body having an upwardly open cavity and laterally exposed surfaces extending in different directions from each other, a protective cover including a main portion dimensioned to serve as a closure for the cavity, and rigid depending flanges adapted to enclose the lateral surfaces, a plurality of rigid obliquely disposed tie members connected at their ends to said flanges in a manner to engage a portion of the lower edge of the fixture, and locking means arranged to preclude unauthorized removal of the cover.

3. In combination with an upright support, a plumbing fixture including a body having an upwardly open cavity and a depending skirt having laterally exposed surfaces extending in opposite directions from each other, a protective cover including a main portion dimensioned to serve as a closure for the cavity, and rigid depending flanges connected

to said main cover portion and arranged for encasing the laterally exposed surfaces of the skirt, a plurality of rigid obliquely disposed tie members connected at their ends to said flanges in a manner to engage a portion of the lower edge of said skirt to prevent upward movement of said cover, said tie members each having a transversely extending lug adapted to engage against the inner surface of said skirt portion of the fixture to prevent lateral movement of the cover in a direction away from the upright support, and locking means connected to said tie members arranged to preclude unauthorized removal of the cover.

4. In combination with an upright support, a plumbing fixture including a body having an upwardly open cavity and a depending skirt having laterally exposed surfaces extending in different directions from each other, a protective cover including a main portion dimensioned to serve as a closure for the cavity, and a pair of rigid depending end flanges terminating adjacent said upright support and connected together at their opposite ends by a rigid depending side flange, said flanges being dimensioned to substantially enclose the laterally exposed surfaces of the fixture skirt, a pair of rigid obliquely disposed tie members each connected at one end to one of the end flanges, and at their other ends to the side flange, a locking bar inter-connecting said last mentioned ends of the tie members, said tie members being arranged to engage the lower edge of the skirt portion of the fixture and provided with a pair of upwardly extending lugs located for engaging the inner surface of said depending skirt portion, and locking means connecting one end of one of said tie members and the locking bar for precluding unauthorized removal of the cover.

5. In combination with an upright support, a plumbing fixture mounted adjacent said support, including an upwardly open cavity and laterally exposed surfaces, a protective cover including a main section dimensioned to serve as a closure for the cavity and having one edge terminating adjacent the upright support, rigid depending flanges connected to the main cover section and arranged to enclose the laterally exposed surfaces of said fixture, means for preventing lateral movement of the cover in the direction away from the upright support, means connected to the flanges and including a lock device for precluding unauthorized removal of the cover.

6. In combination with an upright support, a plumbing fixture mounted adjacent said support, including an upwardly open cavity and laterally exposed surfaces, a protective cover including a main section dimensioned to serve as a closure for the cavity and having one edge terminating adjacent

the upright support, rigid depending flanges connected to the main cover section and arranged to enclose the laterally exposed surfaces of said fixture, a depending lug secured to the under side of the cover and dimensioned for engaging the inner surface of said cavity of the fixture for preventing lateral movement of the cover in the direction away from the upright support, and locking means connected to said flanges and arranged for precluding unauthorized removal of the cover.

7. In combination with an upright support, a plumbing fixture mounted adjacent said support, including an upwardly open cavity and a depending skirt having laterally exposed surfaces extending in different directions from each other, a protective cover including a main section dimensioned to serve as a closure for the cavity, having one edge terminating adjacent said upright support, and rigid depending end flanges connected to said main cover section having one edge thereof terminating adjacent said support, and a rigid depending side flange connected to said main cover section and connected at its ends to said end flanges, means engaging the inner surface of the cavity of the fixture for preventing lateral movement of the cover in the direction away from the upright support, a pair of rigid obliquely disposed tie members each connected at one end to one of the end flanges and their opposite ends to said side flange, said tie members being disposed for engaging a portion of the lower edge of said skirt of the fixture for preventing movement of said cover in an upwardly direction, and locking means connected to said last mentioned ends of the tie members for precluding unauthorized removal of the cover.

In testimony whereof, I have hereunto set my hand at Chicago, Illinois, this 24th day of February, 1930.

JOHN H. McCANN.
